UNITED STATES PATENT OFFICE.

LEONARD F. DUNN, OF ONEIDA, NEW YORK.

ARTIFICIAL TOOTH.

SPECIFICATION forming part of Letters Patent No. 627,720, dated June 27, 1899.

Application filed March 23, 1899. Serial No. 710,178. (No model.)

To all whom it may concern:

Be it known that I, LEONARD F. DUNN, of Oneida, in the county of Madison, in the State of New York, have invented new and useful 5 Improvements in Artificial Teeth, of which the following, taken in connection with the accompanying drawings, is a full, clear, and exact description.

This invention has special reference to the 10 attachment of porcelain veneers to the metal backing which forms part of the main stay of the artificial tooth when mounted on the crown or bridge.

The object of my invention is to provide 15 more convenient and more secure means for attaching the porcelain veneer to the metal backing without danger of injuring the said veneer by the heat imparted to the backing in the process of applying solder thereto and 20 which improved attachment shall also permit the veneer to be readily renewed when required and shall also obviate liability of misfits of the attaching devices; and to that end 25 the invention consists in the novel construction and combination of parts hereinafter described.

The accompanying drawings illustrate in 30 segregated and in combined conditions the component parts of my improved veneer attachment.

Figures 1 and 2 are side and rear face views of the veneer. Figs. 3 and 4 are face and edge views of the metal backing. Figs. 5 and 35 6 are face and edge views of the guard-plate which is employed to prevent the solder from clogging the slots in the metal backing. Fig. 7 is a rear face view of the veneer attached to the metal backing. Fig. 8 is a vertical transverse section on line X X in Fig. 7, and Fig. 40 9 is a side view of the completed tooth.

My improved veneer-fastening consists of the stud *a*, which is rigidly secured to the porcelain veneer *b* and projects from the back of said veneer and is formed with a head *a'* on its free end. This veneer is attached to a metal backing *c*, consisting of a plate which is provided with a vertical slot *d* of uniform width throughout its length and terminating in an enlarged orifice *d'*, usually adjacent to 45 the intended free end of the tooth. The plate or backing *c* is of a thickness equal to 50 the length of the projecting portion of the

shank of the stud *a*, and the slot *d* is of a width approximately equal to the thickness of the aforesaid shank, while the orifice *d'* is 55 of a diameter approximately equal to the diameter of the head *a'* of the stud. I preferably provide the backing *c* with two of the aforesaid slots and orifices and attach to the veneer *b* a corresponding number of studs *a*, 60 as shown, to obtain a more secure fastening of the veneer to the backing. The studs are in the same relative position as the orifices *d* *d'*, and in attaching the veneer *b* to the backing *c* the heads *a'* of the studs are passed 65 through said orifices and then the veneer *b* is pushed toward the base of the backing *c*, and in said operation the shanks of the studs slide in the slots *d*, while the heads *a'* of the studs bear on the back of the backing *c*, and 70 thus effectually interlock the studs with the backing. By making the slots *d* of uniform width throughout their lengths I enable the backing *c* to interlock with studs *a*, located at different distances from the base of the 75 veneer, and therefore I obviate the liability of misfits of the attaching devices of the veneer. The heads *a'* are subsequently covered by the body *f* of solder applied to the rear face of the backing *c*. In order to permit 80 said solder to be applied to the backing while the veneer *b* is removed therefrom, and thus obviate heating and injuring the porcelain veneer, I employ a guard-plate *e*, which I fasten to the rear face of the backing, preferably by means of solder, before applying the body *f* of solder. Said guard-plate is provided with vertical slots *e* *e'*, each of which is of a width approximately equal to the diameter of one of the heads *a'* and of sufficient 85 length to allow the head to freely travel in the slot *e'* in the operation of applying the veneer to the backing in the manner hereinbefore described.

In practicing my invention I proceed as follows, to wit: Before applying the veneer *b* to the backing *c* I temporarily fill the slots *e* *e'* of the guard-plate *e* with a suitable material to exclude from said slots the solder which is subsequently applied to the backing to form 90 the inner portion of the tooth, as shown at *f* in Fig. 9 of the drawings. After this has been accomplished I remove the aforesaid stop-out material from the slots *e* *e'* and apply the ve- 95

neer *b* to the backing *c* by putting wax into the slots in the backing and after warming and softening the wax passing the heads *a'* of the studs *a* through the orifices *d'* and pushing the veneer toward the opposite ends of the slots *d*, and thereby causing the heads *a'* to become interlocked with the backing *c*, as hereinbefore described. I then place the backing, with the veneer temporarily secured thereto, upon the crown or bridge and secure it thereon by means of a small amount of plaster-of-paris placed on the backing and crown or adjacent teeth. I then remove the veneer *b* from the backing and permanently solder the latter to the crown or bridge. After this is effected I replace the veneer on the backing in the manner hereinbefore described with cement interposed between them.

I do not limit myself to the use of the guard-plate *e*, inasmuch as the backing *c* may be made of a plate of sufficient thickness to allow the slots *d*, with the orifices *d'*, to be formed in the plate without extending entirely through the plate. Such construction can be accomplished by means of suitable milling-tools. Said guard-plate may also be dispensed with where a thin backing is required, as is sometimes the case on front teeth or when a cheaper class of work is desired. In such cases I remove a portion of the cement after the veneer has been secured to the backing and fill the space with amalgam, covering the heads of the studs.

I do not confine myself to the arrangement of the orifices *d* *d'* in the end portion of the backing adjacent to the intended free or cutting end of the tooth, as hereinbefore stated, inasmuch as it may be desirable on bridge or dummy teeth to have the aforesaid orifices in the opposite end portion of the backing to allow the veneer to be pushed toward the cut-

ting or grinding end of the tooth in the operation of securing the veneer to the backing.

What I claim as my invention is—

1. In crown and bridge work of artificial teeth the combination, with the veneer front, of the metallic backing provided with a vertical slot of uniform width throughout its length and terminating in an enlarged orifice at one end and a stud projecting from the veneer front and of a diameter approximately equal to the width of the aforesaid slot and formed on its free end with a head of a diameter approximately equal to the diameter of the aforesaid orifice and larger than the adjacent vertical slot, all constructed to permit the veneer to be fastened to the backing by introducing the head of the aforesaid stud through the orifice in the backing and pushing the veneer vertically on said backing and thereby causing the head of the stud to become interlocked with the backing at opposite sides of the vertical slot thereof substantially as described and shown.

2. In crown and bridge work for artificial teeth the combination, with the veneer front, of the metal backing provided with a vertical slot terminating in an enlarged orifice at one end, a stud projecting from the veneer and of a diameter to permit its sliding in the aforesaid slot and formed on its free end with a head of a diameter to pass through the aforesaid orifice and a guard-plate fastened to the rear face of the aforesaid backing and provided with a vertical slot of a width approximately equal to the diameter of the head of the aforesaid stud substantially as and for the purpose set forth.
